EX

DE 379

OF D 17,765

DESIGN.

W. T. GOUCH.

CARPET.

No. 17,765.

Patented Oct. 11, 1887.

UNITED STATES PATENT OFFICE.

WILLIAM T. GOUGH, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 17,765, dated October 11, 1887.

Application filed August 30, 1887. Serial No. 248,314. Term of patent 3½ years.

To all whom it may concern:

Be it known that I, WILLIAM T. GOUGH, of Yonkers, county of Westchester, and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design is adapted for the border of a stair-carpet. It has an inner margin ornamented with conventionalized forms. The

middle portion of my border is covered with 20 a succession of similar groups of circular flower forms. Each group has a large circular flower in the center, around which are gathered small star shaped flowers above and radiating leaves below. A large and prominent circular flower is placed between each group and the group 25 adjoining it. Above these groups are brace-like forms and other line ornamentation.

What I claim as new, and desire to secure by Letters Patent, is—

The design for a carpet-border, consisting of 30 the design substantially as shown.

WM. T. GOUGH.
